(57) **CLAIM**

The ornamental design for a phone case, as shown and described.

DESCRIPTION

FIG. 1 is a front perspective view of a phone case showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a partial enlarged view of the selected portion 9 in FIG. 2.

The dash-dash broken lines shown in the drawings depict portions of the phone case that form no part of the claimed design. The dot-dash broken line circles in FIGS. 2 and 9 are provided for the purpose of indicating the portion included in the enlarged view and form no part of the claimed design.
